UNITED STATES PATENT OFFICE

WILLIAM WOOP, OF FARMINGDALE, NEW YORK

AQUATIC DEVICE

Application filed February 28, 1929. Serial No. 343,542.

This invention relates to aquatic devices, and the improvements are directed to novel and unique means for facilitating instruction in swimming.

5 An important object of the invention resides in the provision of means for supporting a person upon the surface of the water while learning to swim.

10 Another object is to provide a rotatable tower, positioned above the surface of the water, said tower being provided with arms pivotally disposed and carrying sling elements for supporting a person upon the surface of the water.

15 Still another object of the invention resides in the provision of means whereby said arms may be elevated or lowered in accordance with the varying conditions of tide height.

20 With these objects in view, together with others which will appear as the description proceeds, the invention resides in the novel formation, combination, and arrangement of parts, all as will be described more fully hereinafter, illustrated in the drawings, and particularly pointed out in the claims.

In said drawings:

Figure 1 is an elevation of my improved structure, one of the arms being shown in an elevated position.

Fig. 2 is a top plan view thereof.

Fig. 3 is a horizontal sectional view taken substantially on the line 3—3 of Fig. 1.

25 Fig. 4 is a similar sectional view taken on the line 4—4 of Fig. 1 and looking in the direction of the arrows.

Fig. 5 is a sectional view of the platform and taken on the line 5—5 of Fig. 1.

40 Fig. 6 is a sectional detail of the drum and ratchet arrangement, slightly enlarged, and taken on the line 6—6 of Fig. 1.

Fig. 7 is a detailed view showing the pivotal connection between one of the arms and a sling.

45 Figs. 8, 9 and 10 illustrate the harness elements as associated with the user and a sling.

Referring now more in detail to the accompanying drawings, wherein like characters of reference denote similar parts throughout the several views, let 1 represent

a tower, formed preferably of steel or structural iron, and having a fixed base 2, upon which the upper portion 3 is rotatably mounted, said portion 3 being supported upon a base 4, having roller bearing connections with said base 2 and being connected thereto by means of a king pin 5.

Said base 2 is disposed centrally of a platform 6, having a guard rail 7, said platform being adapted to support an operating mechanism as will presently appear. Upon inspection of Figs. 1 and 5 it will be observed that said pin 5 has a squared portion 8 which extends through said base 4, the lower portion 9 of said pin being positioned below the platform 6 and having a sprocket wheel 11 affixed to the extremity 10 thereof. A sprocket chain 12 operatively connects said wheel 11 to a similar wheel 13 carried by the lower end of a shaft 14 which is supported by said platform 6 and adapted to be rotated by means of wheel 15 when it is desired to revolve said tower upon the base 2.

At an intermediate point of the tower, I provide a fixed ring 16 having hinged members 17 to which a series of arms 18 are hinged, said arms having eyes 19 to which the ends of the cables 20 and 21 are attached. The intermediate portions of said cables are each trained over pulleys 22 at the top of the member 3, where they extend downwardly to a drum 23, rotatively carried by said tower and adapted to be operated by a crank 24. As shown in Fig. 6 a ratchet 25 engages the ratchet teeth of wheel 26 on the shaft 27 of said drum, whereby the latter may be held against rotation in one direction. From the above it is obvious that the arms 18 may be raised or lowered whereby the slings 27, pivoted at 28 to the ends 29 of said arms 18, are similarly operated whereby the body of the person 30, supported by said slings, by means of a harness 31, may ride upon the surface of the water whether at low tide as indicated at 32, or at high tide as indicated at 33.

The harness 31 embraces shoulder straps 34 and 35, interconnected by a brace strap 36 and longitudinal body straps 37 and 38, whereby the body 30 will be suspended upon

the water without the straps interfering with the head, neck or limbs of said body 30. The harness also includes straps 39 and 40, one extending under the arms to the straps 37 and 38, and the other extending around the abdomen of the user, said straps 39 and 40 extending to a point 41 where they are connected to the sling 27. The straps 34 and 35 project upwardly and also connect to the arms 42 and 43 of the sling 27 at a point above the connections 41.

The sling 27 may be U-shaped at its lower end through a U-bar 44, which may be connected to or detached from the terminal of the arms 42 and 43 as desired, depending upon the efficiency of the user. The upper ends of the arms 42 and 43 terminate in flat disks 45 to which a pivot pin 46 in the end 29 projects whereby the sling 27 may rotate upon the pivot with the movement of the arm 18, in order that it will always be in a vertical position, but through the arrangement of said flat disk upon the flat sides 47 of the arms 18, the sling will not be able to swing transversely of the arms.

I claim:

1. An aquatic device comprising a base adapted to be positioned in a body of water, a tower carried thereby and positioned above the surface of the water, arms pivotally supported by said tower, a sling disposed at the end of each of said arms and means for elevating and lowering said slings in unison in accordance with varying level conditions of the body of water.

2. An aquatic device comprising a base adapted to be positioned in a body of water, a platform supported by said base and positioned above the surface of the water, a tower mounted on said platform, arms pivotally supported by said tower, a sling disposed at the end of each of said arms and means for elevating and lowering said slings in unison and in accordance with varying level conditions of the body of water.

3. An aquatic device comprising a base adapted to be positioned in a body of water, a platform supported by said base and positioned above the surface of the water, a tower rotatively mounted on said platform, arms pivotally supported by said tower, a sling disposed at the end of each of said arms, means for elevating and lowering said slings in unison and in accordance with varying level conditions of the body of water and means for rotating said tower.

WILLIAM WOOP.
